ROLL-ON BOOK WRAP

Clyde R. Fickes, Des Moines, Iowa, assignor to Hoerner Boxes, Inc., Keokuk, Iowa, a corporation of Delaware
Filed Mar. 16, 1964, Ser. No. 351,986
7 Claims. (Cl. 229—40)

This invention relates to a carton for wrapping books for shipping or mailing and more particularly to a book wrap having improved strength characteristics as well as improved sealing and opening features.

There are many types of book wrap cartons presently on the market, most of which fail to provide adequate protection for the ends and corners of the book. A number of specially designed book wraps are available which utilize cellular inserts to protect the ends of the book and in some instances air cells of special design. When a cellular insert is used, special assembling is required to mount the insert in the box. The air cell type cartons generally are designed to be sealed by means of special machinery. This involves a further expenditure in order to use these book wraps.

One object of the present invention is to provide a book wrap which can be automatically sealed on standard equipment.

Another object of the present invention is to provide a book wrap which protects the article to be shipped from damage due to impact.

A further object of the present invention is to provide a book wrap that can be easily opened by the use of a tear strip.

Still another object of the present invention is to provide a book wrap that can be readily adjusted to accommodate different thickness books.

A still further object of the present invention is to provide a book wrap that has a self-locking closing system.

These objects are accomplished by dividing a single blank of carton-forming material into inner, bottom and top panels separated by end walls hingedly connected to said panels. One of said end walls is hingedly connected by slit scores along a substantial length of the hinge so that the end wall can be used as a tear strip. The inner panel has end wall sections hingedly connected to each end of the panel with an overlay section hingedly connected to said inner panel end walls. Wing flaps are hingedly connected to each end of the overlay sections which act as spacers at each end of the box. End flaps on the top and bottom panels are folded into engagement with the projecting ends of the wing flaps so that an air space or cell is provided between the flaps and the end walls. This space acts to cushion any hard blows or bumps which may be encountered in shipping or mailing. The overlapped end flaps can be sealed in a conventional sealer or self-locking tabs can be provided through the end flaps.

Other objects and advantages will become more readily apparent from the following detailed description when read in connection with the accompanying drawings, in which:

FIG. 1 is a diagrammatic view of a carton blank.

FIG. 2 is a view of the blank folded to the intermediate position, and

FIG. 3 is a view of the blank completely folded with a part of the tear-type end wall turned back.

Referring more specifically to the drawings, the roll-on book wrap is made from a single blank 10 of corrugated material having flutes running transverse to the longitudinal axis of the blank. The blank is divided into an inner panel 12, top panel 14 and bottom panel 16 separated by a tear-type side wall 18 and side wall 19. Slit scores 20-22 are made in the hinged connections of the tear-type side wall with a small hinged connection 21, 23 left at the end of each of the slit score lines. The end

2

can be torn from the blank by merely pulling on tab 25. Score lines 24-26 provide the hinged connection between the other side wall and the inner and top panels. End flaps 28 and 30 are hingedly connected to the bottom panel by score lines 32 and 34 and end flaps 36 and 38 are hingedly connected to the top panel by score lines 40 and 42.

End walls 44 and 46 are hingedly connected at one side to the inner panel by score lines 48 and 50 and to overlap sections 52 and 54 by score lines 56 and 58. Wing flaps 60, 62, 64 and 66 are hingedly connected to the ends of the interlocking sections by score lines 61, 63, 65 and 67. The wing flaps are made longer than the width of the overlap sections by separating the ends of the wing flaps from end flaps 44, 46 by slits 68, 70, 72 and 74. Slits 68, 72 are extended inward a short distance to separate raised sections 76 and 78 from the end flaps.

Two small tabs 80 are provided in each of the end walls adjacent to score lines 48 and 50. These tabs when turned inward, act as spacers to hold a book of less thickness than the width of the end walls from rattling in the box. The tabs shown are designed to provide a book wrap for two different thickness books but it should be apparent that the tabs can be cut to accommodate any of a number of different thickness books.

A book is wrapped in the carton by placing it on the inner panel 12. End walls 44 and 46 are folded upward along both of the ends of the book and overlap sections 52 and 54 folded inward over the top of the book. The wing flaps 62, 66 are folded downward into alignment with score line 22 and wing flaps 60, 64 folded downward into alignment with score line 26. The wing flaps should abut the ends of the end walls 44 and 46. A small portion of the wing flaps will project outward beyond side walls 44 and 46 with wing flaps 60 and 64 in side by side relation to side wall 19. End flaps 36 and 38 are then turned upward into engagement with the projecting end of the wing flaps.

The folded inner and top panels are then folded over side wall 22 onto bottom panel 16 with the surface of inner panel 12 in surface contact with the surface of the bottom panel. End flaps 28 and 30 are then folded upward against end flaps 36 and 38. An adhesive is normally applied to the overlapping surfaces of the end flaps to seal the carton. This adhesive may be applied by any of the conventional gluing machines such as the Seco Case sealer. The end flaps may also be stitched or self-locking tabs 86 (shown dotted) can be provided in each of the end flaps that merely have to be pushed in to interlock the end flaps. The blank is cut and scored so that a close fit is provided along all seams to protect the book from foreign matter. Raised sections 76 and 78 close a gap that normally is present between the edge of bottom panel 16 and the score line 26.

To open the carton, the tear-type side wall 18 is torn along the slit score lines by pulling on tab 25. Once this side wall has been completely removed, wing flaps 62 and 66 can be turned on score lines 63 and 67 to open the side of the carton completely.

Although only one embodiment of the present invention has been shown and described, it should be apparent that various changes and modifications can be made without departing from the scope of the appended claims.

I claim:

1. A carton wrapper formed from a single blank of carton forming material, comprising
an inner panel hingedly connected to one edge of a pair of end walls and to one edge of a side wall, each of said end walls being folded to a normal position with respect to said inner panel,
overlapping sections hingedly connected to the other

edges of said end walls, said overlapping sections being folded to a substantially parallel relation with respect to said inner panel,
 wing flaps having one edge hingedly connected to each end of each of said overlapping sections, said wing flaps being folded to a parallel relation with respect to each other and into abutting engagement with the ends of said end walls, one end of each of said wing flaps projecting outward beyond said end wall, said side wall being folded to a normal position with respect to said inner panel, 5
 a top panel having one edge hingedly connected to the other edge of said side wall and having end flaps hingedly connected to each of its ends, said top panel being folded over and into engagement with said overlapping sections, said top panel end flaps being folded into engagement with the projected ends of said wing flaps, 15
 a second side wall having one edge hingedly connected to said other edge of said top panel and being folded to a normal position with respect to said top panel and inner panel,
 a bottom panel having one edge hingedly connected to the other edge of said second side wall, and end flaps hingedly connected to the end edges of said bottom panel, said bottom panel being folded into engagement with the inner panel with the end flaps on said bottom panel folded into engagement with the end flaps on said top panel, 20
 2. A carton wrapper according to claim 1 wherein the hinged connections for said second side wall are slit scored throughout substantially their full length to provide a tear strip for opening the wrapper. 25
 3. A carton wrapper according to claim 2 including means folded into the space between the end walls and end flaps for securing the end flaps on said bottom panel with the end flaps on said top panel to form a closed container.
 4. A carton wrapper according to claim 1 wherein the end walls of said inner panel are spaced from the end flaps on said top panel to thereby form an air space at each end of the carton. 30
 5. A roll-on type wrap for wrapping and mailing books, formed from a single blank of carton forming material, comprising 35

40

45

an inner panel for initially supporting said book, a pair of end walls hingedly connected to the edges of said inner panel and folded into engagement with the ends of said book,
 a pair of overlapping sections hingedly connected to said end walls and folded to a substantially parallel relation with respect to said inner panel,
 a wing flap hingedly connected to each of the ends of said overlapping sections and folded into engagement with the ends of said end walls, one end of each of said wing flaps projecting beyond the end walls,
 a side wall hingedly connected to said inner panel and folded into abutting engagement with two of said wing flaps,
 a top panel hingedly connected to said side wall and having end flaps hingedly connected to each of its ends, said top panel being folded over said overlapping sections with the end flaps folded into engagement with the projecting ends of said wing flaps to form an air space between the end flaps and the side walls,
 a second side wall hingedly connected to said top panel and folded into abutting engagement with the other two wing flaps, and
 a bottom panel hingedly connected to said second side wall and having end flaps hingedly connected to each end, said bottom panel being folded into engagement with the inner panel with the end flaps folded into engagement with end flaps on the bottom panel.
 6. A roll-on type wrap according to claim 5 wherein said end walls include tab means folded into the space between the end walls to hold said article in position within said formed wrapper when the thickness of the article is substantially less than the width of the end wall.
 7. A roll-on type wrapper according to claim 5 wherein said end flaps on said top and bottom panels include self-locking means for interengaging said end flaps.
